Inventor

UNITED STATES PATENT OFFICE.

JAMES A. DAWLEY, OF DENVER, COLORADO.

DESIGN FOR A PIN OR BADGE.

SPECIFICATION forming part of Design No. 21,224, dated December 8, 1891.

Application filed September 19, 1891. Serial No. 406,262. Term of patent 3½ years.

To all whom it may concern:

Be it known that I, JAMES A. DAWLEY, a citizen of the United States, residing at Denver, in the county of Arapahoe and State of Colorado, have invented and produced a new and original Design for Pins and Badges, of which the following is a specification, reference being had to the accompanying drawing, forming a part thereof.

10 The figure is a front view of the pin or badge, showing my design.

The leading feature of my design is a log of wood 1 and a dove 3, with a palm branch in its mouth, sitting upon the same. Attached

15 to the log of wood 1 by two small chains is a shield 4, bearing on the face of it an ax 5 and beetle 6 crossed, in front of which is a palm-tree 7, with a wedge 8 lying at its foot. Upon the lower part of the shield are inscribed nine stars 9.

20

What I claim is—

The design for a badge or pin herein shown and described.

JAMES A. DAWLEY.
